CLAIM

The ornamental design for a combined portable food and condiment container, as shown and described.

DESCRIPTION

FIG. 1 is a perspective view of a first embodiment of a combined portable food and condiment container showing my new design in an open position;

FIG. 2 is a perspective view thereof in a closed position;

FIG. 3 is a top plan view; in the open position;

FIG. 4 is a front elevational view thereof;

FIG. 5 is a right side elevational view with the left side being a mirror image thereof;

FIG. 6 is a bottom plan view thereof; and,

FIG. 7 is a perspective view of a second embodiment of FIG. 1 in the open position.

The undisclosed rear view of the first embodiment if unornamented.

The undisclosed views of the second embodiment are the same as the views of the first embodiment with the exception of the location of the condiment container.
